UNITED STATES PATENT OFFICE.

LOUIS LUCAS, OF JAMESTOWN, NEW YORK.

CANDLESTICK.

1,316,624.

Specification of Letters Patent. Patented Sept. 23, 1919.

Application filed January 23, 1919. Serial No. 272,651.

To all whom it may concern:

Be it known that I, LOUIS LUCAS, a citizen of the United States, residing at the city of Jamestown, in the county of Chautauqua 5 and State of New York, have invented certain new and useful Improvements in Candlesticks, of which the following, taken in connection with the accompanying drawings, is a specification.

10 The invention relates to holders for candles and similar articles; and the object of the improvement is to provide a simple and durable sheet metal candlestick in which the two parts may be quickly and easily 15 struck up and assembled by means of suitable dies at low cost, providing a strong and durable candlestick which is adaptable to all sizes of candles and similar articles to be held upright; and the invention consists 20 in the novel features and combinations hereinafter set forth and claimed.

In the drawings, Figure 1 is a perspective view of the candlestick with a candle in dotted outline therein. Fig. 2 is a crosswise 25 sectional view of the candlestick showing the construction and arrangement of the same. Fig. 3 is a plan view of the blanked out metal sheet for the saucer portion of the candlestick before shaping; and Fig. 4 is a 30 similar view of the upper resilient clasping portion before shaping by means of suitable dies, the two parts when assembled forming the completed candlestick. Fig. 5 is a perspective view of the upper or clasp portion 35 of the candlestick separated from the lower or saucer portion.

Like characters of reference refer to corresponding parts in the several views.

In the drawings, the numeral 10 designates the saucer shaped lower portion which 40 is struck up from sheet metal in attractive designs, being shown square and having an integral handle 11 at one side extending outward from the curved rim 12.

45 The candle or similar article is supported in an upright position within the saucer by means of the spring clasp shaped portion 13 which is made with a wide base 14 so as to give a bracing strength to each of the tapered jaws 15 of the spring clasp 13. The 50 jaws 15 are turned upward at 16 on each

side along the line of the base 14. The tops of the jaws 15 are each slightly curved to fit the round sides of the candle. The central portion 14 is made broad and square so as 55 to form a square firm base which firmly supports the candle central of the saucer 10 with a spring clasp jaw 15 on each side.

The spring clasp portion 13 is attached to the saucer 10 by means of interlocking lugs, 60 17 on the saucer and 18 on the clasp portion 13, which lugs 17 and 18 are struck from the sheet metal by the forming dies, suitable shaping dies following the forming dies in shaping the two parts, as shown. One of 65 the lugs, preferably 17, is cut short sufficiently to insure the easy insertion of the other lug 18 through the hole 19 made by shortening the lug 17, and the shortened lug 17 then passes up through the hole made 70 by striking out the lug 18. The shaping dies for the clasp portion 13 also press the two lugs 17 and 18 into flat cohesion with one another so as to form a substantially flat 75 surface on the upper and under sides so that the butt of the candle has a flat support.

It is accordingly apparent that the parts may be quickly and easily struck up at low cost, preferably from sheet brass, and the assembling process becomes a part of the 80 shaping and forming thereby providing a strong and durable construction which may be made in pleasing designs as desired; and that the clasp portion is firmly held by the broad base 16 and interclasping lugs 17 and 85 18 as well as by the firm pressure of the metal parts upon one another during the process of assemblage. The spring jaws 15 may be compressed toward one another or pressed apart. 90

I claim as new:—

1. A candlestick comprising a struck up sheet metal saucer having a lug struck from the central portion thereof, a spring clasp portion having a flat base, and a lug struck 95 from said flat base which interfits with said lug in said saucer to firmly interlock said parts together when assembled under pressure.

2. A holder for candlesticks and similar 100 articles comprising an upper clasp portion having adjustable spring jaws and a broad

base, a lower saucer shaped portion having a struck up lug central thereof, a lug struck from the central portion of said broad base of said clasp portion interfitting with said lug in said saucer and pressed together in holding engagement to firmly support said clasp portion in an upright position on said broad base in the center of said saucer, and

a handle on the rim of said saucer integral therewith.

In testimony whereof I have affixed my signature in the presence of two witnesses.

LOUIS LUCAS.
